DESIGN FOR A DISPLAY CASE

Cyrus F. Hoffman, Trenton, N. J., assignor to
C. V. Hill & Company, Incorporated, Trenton,
N. J., a corporation of New Jersey

Application August 6, 1938, Serial No. 79,165

Term of patent 14 years

To all whom it may concern:

Be it known that I, Cyrus F. Hoffman, a citizen of the United States, residing at Trenton, in the county of Mercer and State of New Jersey, have invented a new, original, and ornamental Design for a Display Case, of which the following is a specification, reference being had to the accompanying drawings, forming a part thereof.

Fig. 1 is a perspective view showing the front and end of a display case embodying my design.

Fig. 2 is a perspective view showing the rear and end of the display case illustrated in Fig. 1.

Fig. 3 is a top plan view of the display case illustrated in Fig. 1.

Fig. 4 is a rear view of the display case illustrated in Fig. 1, and

Fig. 5 is an end view of the display case illustrated in Fig. 1.

This application is a continuation-in-part of my application Serial No. D-73,700 filed December 18, 1937.

The essential feature of the design of the present invention consists in the general outline of the display case comprising a substantially flat top, vertical ends and vertical lower portions of the front and rear of the case with the upper portion of the front of the case inclined rearwardly and with the doors in the upper portion of the rear of the case lying within surfaces defined by the end members and formed with forwardly inclined and rounded upper edges extending substantially to the top of the case.

I claim as my invention:

The ornamental design for a display case, substantially as shown and described.

CYRUS F. HOFFMAN.
